(57) **CLAIM**

The ornamental design for a sling keeper comprised of a handle, a nut, and a holder, as shown and described.

DESCRIPTION

FIG. 1 is a right, front side perspective view of an embodiment of a sling keeper comprised of a handle, a nut and a holder, according to the present disclosure;

FIG. 2 is a bottom, right, front side perspective view of the embodiment of FIG. 1;

FIG. 3 is a bottom, front side perspective view of the handle and nut separated from the holder of the embodiment of FIG. 1;

FIG. 4 is a bottom, right, front side perspective view of the handle separated from the nut and the holder of the embodiment of FIG. 1; and,

FIG. 5 is a top, front side perspective view of the nut separated from the handle and the holder of the embodiment of FIG. 1; and,

FIG. 6 is a top, right, front side perspective view of the holder separated from the handle and the nut of the embodiment of FIG. 1.

The broken lines represent environment that form no part of the claim.
